DESIGN FOR A COFFIN HANDLE

Lawrence J. Clark, Lakewood, Ohio, assignor to
The Dickey-Grabler Company, Cleveland,
Ohio, a corporation of Ohio

Application May 23, 1935, Serial No. 56,976

Term of patent 7 years

To all whom it may concern:

Be it known that I, Lawrence J. Clark, a citizen of the United States, residing at Lakewood, in the county of Cuyahoga and State of Ohio, have invented a new, original, and ornamental Design for Coffin Handles, of which the following is a specification, reference being had to the accompanying drawing, forming part thereof, and wherein Fig. 1 is a front elevation of a coffin handle showing my new design; Fig. 2 is a end elevation thereof, and Fig. 3 is a section on the line 3—3 of Fig. 1.

The shape of the part shown in dotted lines is unessential to the design.

I claim:

The ornamental design for a coffin handle as shown and described.

LAWRENCE J. CLARK.
